UNITED STATES PATENT OFFICE.

JOHN EINSFIELD, OF ONEIDA, NEW YORK, ASSIGNOR TO CHAPPELL, CHASE, MAXWELL & CO., OF SAME PLACE.

DESIGN FOR A BURIAL-CASKET.

SPECIFICATION forming part of Design No. 18,009, dated January 10, 1888.

Application filed November 14, 1887. Serial No. 255,167. Term of patent 7 years.

To all whom it may concern:

Be it known that I, JOHN EINSFIELD, of Oneida, in the county of Madison, in the State of New York, have invented a new and original Design for Burial-Caskets, of which the following, taken in connection with the accompanying drawings, is a full, clear, and exact description.

This design pertains to the ornamentation of the corners of the exterior of burial-caskets, as hereinafter described, and specifically pointed out in the claims.

The design is fully illustrated in the annexed drawings, in which—

15 Figure 1 is a top plan view of the casket. Fig. 2 is a side elevation of the same; and Fig. 3 is a horizontal transverse section on line *xx*, Fig. 2.

Similar letters of reference indicate corresponding parts.

20 A represents the casket proper, and C the lid thereof. The base of the body and the top edges of the lid are usually ornamented by a suitable molding, *c*, extending along the sides and ends of the casket, and heretofore met at the corners of the casket and its lid.

25 By my design I further embellish the casket and its lid by horizontally-projecting enlargements *aa* of the bases of the corners thereof, as shown in the annexed drawings.

I do not limit myself to any particular shape of the enlargement, but prefer to have the contour of the horizontal plane of the said enlargement of segmental form, as illustrated in 35 the accompanying drawings, and also prefer

to have the base of the enlargement in the same plane and of the same height as the base of the moldings to which I join the enlargement, and the top portion, *a'*, of the enlargement to project outward from the top of the 40 moldings and flared toward the base, and concaved or otherwise ornamented on top, to harmonize with the style of the moldings. The top of the lid I also embellish by rectangular panels *PP* and *P'*, surrounded by raised moldings *bb*. 45

What I claim as new is—

1. In a design for a burial-casket, the top consisting of the rectangular panels *PPP'*, with raised moldings *bb* around them, the 50 molding *c* along the edges of said top, and the horizontally-projecting enlargements *aa* at the corners, substantially as described and shown.

2. The design for burial-caskets, consisting of the side and end moldings, *cc*, and the horizontally-projecting enlargements *aa* at the corners, and having their base of the same height as the base of the moldings, and the top portion, *a'*, of the enlargement projecting outward from the top of the moldings and 60 flared toward the base, substantially as described and shown. 55

In testimony whereof I have hereunto signed my name, in the presence of two witnesses, at Oneida, in the county of Madison, in the State 65 of New York, this 5th day of November, 1887.

JOHN EINSFIELD. [L. S.]
